CLAIM

The ornamental design for a cable conduit, as shown and described.

DESCRIPTION

FIG. 1 is a front perspective view of a cable conduit showing the claimed design;

FIG. 2 is a rear perspective view thereof;

FIG. 3 is a rear view thereof;

FIG. 4 is a front view thereof;

FIG. 5 is a right side view thereof;

FIG. 6 is a left side view thereof; and,

FIG. 7 is a top view thereof.

The shade lines in the drawings show contour and not surface ornamentation.
